UNITED STATES PATENT OFFICE

FRANK THEODORE WILLIAMS AND HAROLD E. ELLIS, OF MERIDEN, CONNECTICUT, ASSIGNORS TO THE MILLER COMPANY, OF MERIDEN, CONNECTICUT, A CORPORATION OF CONNECTICUT

HEATER

Application filed October 28, 1929. Serial No. 402,859.

The present invention relates to heaters, and is more particularly directed toward a portable heater employing liquid fuel.

The present invention contemplates a portable heater having a body made up of sheet metal parts, designed so as to be capable of easy assembly and yet provide a structure of pleasing appearance, and with sufficient strength and rigidity to be of service as a room heater as well as an oil stove. The invention also contemplates a portable room heater provided with a burner and chimney of the type ordinarily used in oil cook stoves, and wherein the fuel supply is carried in two or more tanks.

The arrangement of the fuel supply system is such that fuel will be taken from one of the tanks before it is taken from the other tank, thus making it possible to have a tank of fuel held in reserve, and making it unnecessary to refill two partially emptied tanks.

Other and further objects of the invention will be apparent as the description proceeds.

The accompanying drawings show, for purposes of illustrating the present invention, one embodiment in which the invention may take form, it being understood that the drawings are illustrative of the invention rather than limiting the same.

In these drawings:

Figure 1 is a side elevational view taken in the direction of the arrow 1 of Figure 2, and showing parts and sections on the broken line 1—1 of Figure 4;

Figure 1a is a fragmentary sectional view taken on the same section as Figure 1 but at an enlarged scale;

Figure 2 is an end view taken in the direction of the arrow 2 of Figure 1, and showing, in dotted lines, the cover in partly raised position;

Figure 2a is a fragmentary sectional view of the upper rear corner of the heater as it appears in Figure 2, and showing the support for the cover plate;

Figure 3 is a vertical sectional view on the line 3—3 of Figure 1;

Figure 4 is a horizontal sectional view on the line 4—4 of Figure 1; and

Figure 5 is a fragmentary top plan view showing the grate over the burner.

The base plate of the heater is indicated at 10. It is preferably made of heavy gauge sheet metal pressed downwardly at the edges to form reenforcing walls, 11, 12, 13 and 14. The lower edges of these walls may be doubled back, as indicated at 15 in Figure 1. Four leg forming members 16 are secured to the corners of the base plate 10 by means of bolts indicated at 17. These legs are made out of sheet metal and extend downwardly and outwardly to fit inside of a drip pan indicated at 18. This drip pan is made of sheet metal and is provided with upwardly and inwardly sloping walls, as indicated in the drawings, to cooperate with the outwardly flaring legs whereby the pan remains attached to the legs and may be moved with the heater when it is carried about.

The legs 16 have upwardly extending portions indicated at 19. Side panels 20 and 21 are secured to these upper leg portions by bolts indicated at 22. These side panels have stiffening flanges at their side edges, as indicated at 23, at their bottom edges, as indicated at 24, and at their upper edges, as indicated at 25. The lower edges 24 rest on top of the base plate and the side flanges 23 stiffen the side panels and provide door openings. The upper flanges 25 stiffen the upper edges of these side panels and deflect the heat inwardly.

Near the corners of the side panels, cover plate supporting brackets 26 are secured, as, for example, by welding them in place. These brackets extend above the upper edges of the side panels and support a cover plate 27, this cover plate being secured in place by bolts 28 passing through the brackets 26.

The cover plate 27 has depending flanges indicated at 29 to stiffen the construction and cover the space above the edges of the side panels, as will be clear from Figure 2a. This cover plate extends the entire length of the heater and is provided with an opening 30. A grate 31 of suitable construction is secured to the top cover plate about the opening. This grate may be made out of straps of sheet metal welded to the cover plate and may carry

a centrally located heat deflecting plate 32. Carrying handles 33 are secured to the depending flanges 29 of the cover plate, and a hinged cover 34 is secured to the cover plate 27 by a hinge indicated at 35.

5 The end openings of the heater body are adapted to be closed by doors indicated at 40 and 41. These doors are hinged, as indicated at 42 and 43, to plates 44 and 45, secured to the upper extensions 19 of the legs 16 by

10 bolts 46. The doors may be held in closed position by the catches 47 and 48. The catch may be made out of a knob and bent piece of sheet metal, as indicated, the catch passing up inside of the flange 29 of the coverplate.

15 The inside of the heater body is divided into two compartments or sections by a partition 50, also made of sheet metal, and secured in place by bolts 51 passing through flanges 52. This partition is flanged at the

20 top and bottom, as indicated at 53, to stiffen it. The partition is placed nearer to one end of the body than the other, as will be apparent from the drawings, and carries a channel shaped member 54 forming an air space.

25 The fuel supply system is here shown in the form of two independent fuel tanks or bottles 60 and 61. These bottles are made of glass and are of identical construction. They have the usual threaded cap or cover member 62 and spring pressed needle valve 63, which is adapted to close off the outlet for fuel while the bottle is inverted and until it is placed in the sub-tank. As is clearly shown in Figures

30 1 and 3, the device employs two sub-tanks 64 and 65. These sub-tanks are secured to a base 66, adapted to rest on top of the base 10 of the stove. The tanks are connected together by a tube 67, placed near the bottom of the tank so as to be below the level of the delivery outlet of the bottles, and so that the fuel in the tanks may seek a common level.

35 As shown in the drawings, the sub-tank 64, at the left of Figure 3, is deeper than the sub-tank 65 at the right. This will place the bottle 60 at a slightly higher elevation than the bottle 61 and, hence, the outlet of the bottle 61 will be submerged when the outlet for the other bottle is admitting an air bubble

40 to allow fuel to flow out. The fuel outlet is in the form of a pipe 68, secured to the sub-tank 65 and adapted to pass down through an opening 69 in the base 10. This fuel pipe extends along underneath the

45 base 10 and is provided with a burner connection indicated at 70. The other end of the pipe 68 extends out through the flange 12 of the base plate and is provided with a clean out plug 71.

50 55 60 The burner is indicated at 72. This burner is secured to the burner connection 70 by a coupling indicated at 73. It rests on top of the base plate 10 and is held in place by a circular ring 74, as indicated in Figures

65 1 and 1a. If desired, the burner may be

more securely held in place by a bent wire member indicated at 75, the upper end of this wire member being looped over the cross strap 76 ordinarily employed in the burner, and the lower end 77 being passed through a hole 78 provided in the base 10. The burner 72 may include the usual flame spreader, chimney and other devices ordinarily employed in oil stoves.

70 75 In assembling the heater, the heater body may be completed as a unit and the fuel supply unit assembled to include the sub-tanks 64 and 65, tube 67, base 66, pipe 68, and burner connection 70. This unit is passed in through the door opening at the left and the pipe passed through the hole 69 in the base plate. The entire unit may be moved on into place and the clean out plug 71 secured on the end of the pipe. The burner is then attached and this completes the fixing of the fuel system parts in place.

80 85 In order that the bottles 60 and 61 may be held against accidental upsetting, clips 79, of bent spring metal, are provided. They are secured to a cross strap 80, attached to the flanges 52 of the partition strip 50.

90 95 The side and end walls of the heater body may be provided with air openings about the bottom, as indicated at 81, and about the side and end walls, as indicated at 82. The cover 34 may be provided with ventilation openings, as indicated at 83. The door 41 is provided with the usual side opening 84 to permit observation of the burner.

100 105 When the heater is in use, both tanks may be filled with fuel, but, owing to the fact that one of the tanks is at a higher elevation than the other tank, fuel flows from this tank first. As shown, the tank 60 is the higher one and, hence, the lowering of the fuel will open the inlet of this tank before it opens the inlet of the other tank. If the fuel supply is exhausted from the tank or bottle 60, the fuel will be drawn from the tank or bottle 61.

110 115 The heater is particularly adapted for room heating when a kerosene burner will supply sufficient heat for warming the room. It also has an efficient burner and has a suitable grate whereby it may be used as a single burner oil stove for cooking purposes, the grate 31 being available to support the cooking utensil, or a small oven may be placed over the opening 30.

120 125 It is obvious that the invention may be embodied in many forms and constructions within the scope of the claims, and we wish it to be understood that the particular form shown is but one of the many forms. Various modifications and changes being possible, we do not otherwise limit ourselves in any way with respect thereto.

We claim:

130 1. A portable heater comprising a base, side panels, end panels each having a door, a cover plate supported from the side panels

and spaced above the same, a vertical partition dividing the interior into two compartments to which access may be had by the doors, an oil burner in one compartment, a fuel supply tank in the other compartment, and a fuel pipe connecting the tank and burner.

2. A portable heater comprising a base, side panels, end panels each having a door, a cover plate supported from the side panels and spaced above the same, a vertical partition dividing the interior into two compartments to which access may be had by the doors, an oil burner and a chimney for the oil burner in one compartment, a fuel supply tank in the other compartment, and a fuel pipe connecting the tank and burner, the cover plate having an opening above the chimney and supporting a grate across the opening.

3. A portable heater comprising a base, side panels, end panels each having a door, a cover plate supported from the side panels and spaced above the same, a vertical partition dividing the interior into two compartments to which access may be had by the doors, an oil burner and a chimney for the oil burner in one compartment, a fuel supply tank in the other compartment, a fuel pipe connecting the tank and burner, the cover plate having an opening above the chimney and supporting a grate across the opening, and a hingedly supported cover above the cover plate and covering the grate and opening.

4. A heater comprising a base having downwardly bent sides, legs secured to said sides and extending above the base, side panels secured to the legs, the edges of the panels being flanged inwardly to stiffen the same, straps secured to the top of the side panels, a cover plate secured to the straps, a vertical partition secured to the cover plate base and panels to divide the heater into two compartments, a fuel supply tank in one compartment, and a burner in the other compartment, and connected to the fuel supply tank by a pipe.

5. In a heater, a fuel supply unit comprising a pair of sub-tanks secured to a support and connected together by a tube so that fuel may seek a common level, a fuel pipe connected to one of the tanks and extending below the tank and horizontally to a burner connection outlet, and a sheet metal heater body having a base, a burner compartment and a fuel tank compartment, and a door for the fuel tank compartment, the fuel supply unit being insertible through the door and movable into position to place the burner connection outlet underneath the burner compartment, the pipe extending beyond the burner connection and passing through a side wall of the heater body, and a drain plug for securing the unit in position.

Signed at Meriden, in the county of New Haven and State of Connecticut, this 22nd day of October, 1929.
